UNITED STATES PATENT OFFICE.

LÉON SAIVES, OF BILLANCOURT, FRANCE, ASSIGNOR TO LOUIS RENAULT, OF BILLANCOURT, FRANCE.

CARBURETOR.

Application filed April 20, 1922. Serial No. 555,763.

To all whom it may concern:

Be it known that I, LÉON SAIVES, engineer, citizen of the French Republic, residing at Billancourt, Department of the Seine, in France, and whose P. O. address is 15 Rue Gustave Sandoz, in the said city, have invented certain new and useful Improvements in or Relating to Carburetors; and I do hereby declare the following to be a full, clear, and exact description of the invention, such as will enable others skilled in the art to which it appertains to make and use the same.

The invention relates to an improved carburetor for internal-combustion engines and is illustrated in the accompanying drawings, in which:—

Fig. 1 is a vertical section on line 1—1 of Fig. 2.

Fig. 2 is a vertical section on line 2—2 of Fig. 1.

Fig. 3 is a vertical section on line 3—3 of Fig. 1.

Fig. 4 is a vertical section of a modified form.

Fig. 5 is a similar view of a further modified form.

Referring to Figs. 1, 2 and 3 of the drawings, 1 indicates the body of the carburetor provided with an end flange 2 for the purpose of attaching the carburetor to the engine. The discharge end of the carburetor comprises a generally cylindrical chamber 4' in which is mounted a butterfly valve 5 controlling the cross sectional area of the passage of the gases to the engine. The forward end of the body portion is bell-shaped, as at 3, the opening being protected by a hood 4, the space between the hood and the rim of the bell-shaped opening constituting the main air inlet to the carburetor.

Rigidly secured to a rod 7, mounted in the perforated boss in the hood 4, is a Venturi tube 6, which is thus mounted for axial adjustment in the flaring end 3 of the carburetor, so that the inner edge of said Venturi tube cooperates with the walls of the inner end of the flaring opening 3 to open and close a passage for air to the carburetor, outside of said Venturi tube. The rod 7 is preferably connected to the accelerator button or pedal, as will be understood. A nozzle 8 communicating with a constant level fuel feed chamber is mounted in the lower side of the carburetor with its discharge end

extending through a slot 9 in the lower side of the Venturi tube 6.

In the body of the carburetor and adjacent the minimum diameter of the flaring end 3 thereof is an annular duct 11 provided with a series of openings 10 communicating with the interior of the flaring end 3 adjacent the inner end of the Venturi tube 6. The duct 11 is connected to the constant level feed chamber by an inverted U-shaped passage 65 12 having a return bend 13, in the leg of which adjacent the constant level feed chamber there is located a restricted opening 14. An air inlet tube 15 extends into the passage 13 and terminates at a point above the restricted opening 14, as shown in Fig. 3.

The interior of the body portion 1 is provided with an annular flange 16, to the rear of which is fixed a second Venturi tube 17 mounted in passage 4', the flange 16 and 75 the interior wall of the Venturi tube 17 constituting an annular passage 18, which communicates with an automatic air valve 20 mounted on one side of the carburetor, the communication being established by 80 means of a hood 19.

The action of the carburetor, as described, is as follows: At low speeds of the motor, the Venturi tube 6 occupies the position shown in Fig. 1 with its inner edge engaging 85 the walls of the flaring end 3, and the discharge end of nozzle 8 projecting into the restricted portion of the Venturi tube 6 where the suction is greatest. The air entering the space between the flaring end 3 of the body 1 and the hood 4 is drawn through the bore of the Venturi tube and entrains the fuel delivered by nozzle 8, the mixed air and fuel passing through the opening formed by the flange 16, thence through the second 90 Venturi tube 17, where an additional supply of air is delivered to the mixture by way of air valve 20, the hollow hood 9 and the passage 18 formed between the flange 16 and the interior of the Venturi tube 17, this auxiliary air supply being automatically controlled in accordance with the suction, which is dependent upon the speed of the engine. When the engine is to be operated at normal 95 and high speeds, the rod 7 is actuated to withdraw the Venturi tube 6 from its seat against the walls of the restricted throat of the section 3 of the body portion, thereby opening a direct communication for the air 100 on the outside of the Venturi tube, so that 110

this entering air will entrain the fuel delivered by the annular series of openings 10, thereby augmenting the fuel supply from the nozzle 8. As the nozzle 8 is designed to 5 supply the proper proportions of fuel for operating the engine at low speed and when the discharge end of said nozzle is located in the constricted portion of the Venturi tube, it will be apparent that the slight dim-
 10 inution in the fuel supply in the nozzle 8 will occur when the Venturi tube 6 is retracted by the rod 7 to bring the second fuel supplied by way of the annular series of jet openings 10, into action. However, the com-
 15 bined fuel supplied from the jet nozzle 8 and the annular series of openings 10 is adequate to operate the engine at normal speeds and obviously the speed may be increased by adjusting the Venturi tube outwardly in the
 20 flaring throat 3 of the carburetor, thereby increasing the opening between the Venturi tube and the walls of the flaring opening, so that a large volume of air passes into the carburetor outside of the Venturi tube 6 and
 25 entrains larger portions of fuel from the annular series of openings 10. In the particular modification shown in Fig. 4, the carburetor is arranged vertically, the Venturi tube 6 being actuated by the rod 7 connected
 30 to the accelerator pedal or button and the jet nozzle 8 being in axial alignment with the opening through the Venturi tube. The operation of this device is practically identical with that of the carburetor first described.
 35 In the modification shown in Fig. 5, the

same general arrangement is followed as in Fig. 4, except that the lower portion of the Venturi tube 6, which latter is guided in the bore of the carburetor, is provided with openings or air ports 21, so that the Venturi tube 40 is automatically displaced by the suction produced by the engine, to uncover the annular series of openings 10 during normal or high speeds. The openings 21 admit the air outside of the Venturi tube, when the 45 latter has been displaced; said air sweeping over the openings 10 and carrying the fuel from said openings into the body portion of the carburetor.

What I claim is:

50 A carburetor for internal combustion engines comprising a casing having a longitudinal bore, said bore being enlarged adjacent one end to form an air chamber, a Venturi tube axially movable in said air chamber serving as a primary air inlet and controlling communication between said air chamber and said bore, means for discharging fuel into said Venturi tube, means for discharging fuel into said air chamber adjacent said Venturi tube, a second Venturi tube fixed within said bore in the rear of said adjustable Venturi tube, an auxiliary air chamber communicating with said bore between said Venturi tubes, and suction responsive means for controlling the supply of air to said auxiliary air chamber.

55 60 65 66 In testimony whereof I affix my signature.

LEON SAIRES.
